UNITED STATES PATENT OFFICE

CLIFFORD J. GLEASON, OF WORCESTER, MASSACHUSETTS, ASSIGNEE TO M. S. WRIGHT COMPANY, OF WORCESTER, MASSACHUSETTS, A CORPORATION OF MASSACHUSETTS

VACUUM DRY MOP

Application filed January 27, 1923. Serial No. 615,314.

My invention relates to new and useful improvements in mops of the dry type adapted more particularly for use in connection with the nozzles of vacuum cleaners and has 5 for its principal object the provision of means of a simple character for detachably connecting the mop to the nozzle of the cleaner, it being understood that when I use the term nozzle I refer to either the nozzle forming a part of the cleaner itself or the nozzle of a hand tool such as is attached to the end of a pipe used in connection with stationary or portable vacuum cleaning machines.

Another object consists in constructing the 15 nozzle in a novel manner to cooperate with the strands of the dry mop in such a way that when the suction is applied to the nozzle the strands will be drawn beneath the edge of the nozzle, to form a bearing surface, and 20 for a distance into the slot of the nozzle, the strands being of such a length that they will not clog the nozzle opening.

With these and other objects in view, my 25 invention consists in the novel details of construction and combination of parts as will be readily understood by reference to the following specification when considered in connection with the accompanying drawings in which:—

30 Fig. 1 is a top plan.

Fig. 2 is a transverse vertical section with parts shown in elevation.

Fig. 3 is a fragmental longitudinal vertical section, enlarged, to show the end construction of the nozzle and the position of the 35 mop with respect thereto, and

Fig. 4 is a detail, enlarged, showing one of the fasteners for securing the mop to the nozzle.

40 In the drawings 1 indicates the nozzle, shown as a part of a hand tool, having a recess 2 formed in its under surface, the ends of this recess being curved as shown at 3 and the sides being outwardly flared or 45 curved as shown at 4. An opening 5 extends from the top of the nozzle and communicates with the recess as shown more particularly in Figs. 2 and 3 of the drawings. A plate or casting 6 is secured to the top of the nozzle 50 by means of the screws 7 or other suitable

fastening means and extending from the upper surface of the plate or casting is a sleeve or socket 8 which communicates with the opening 5 and is adapted to receive the end of the handle or pipe forming a part of 55 the tool of the vacuum cleaner. The outer side edges of the nozzle are inwardly beveled towards the bottom as shown at 9 and grooves 10 are formed in the end edges of the nozzle 60 for a purpose which will later appear.

My mop is adapted to be detachably connected to the nozzle and comprises a strip of fabric 11 to which the strands or strings 12 are secured preferably by stitching through a strip 13 which passes through the looped ends of the strands as more clearly illustrated in Fig. 2 of the drawings. These strands or strings 12 are of such a length that when suction is applied to the nozzle they 70 will be drawn beneath the edges of the nozzle and into the recess 2. They are, however, not so long as to allow the ends to extend so far into the recess as to close or clog the opening 5. The beveled side edges 9 hold the strip 11 at such an angle, it being noted that the strip lies flat against the side edges and that the mop strands extend beneath the bottom, so as to position the strands or 75 strings 12 so that they may be easily drawn under the nozzle. The strip 11, when the 80 mop is in position upon the nozzle, will encircle the edges of the nozzle and in order to prevent displacement of the mop but at the same time allowing it to be easily placed in position or removed therefrom I provide 85 the fasteners 14 which consist of the socket portions 15, carried by the strip, and the headed portions 16 secured to the side edges, preferably by the screws 17. Recesses 18 receive the headed portions of the fastener.

90 From the above detail description it is believed that the manner of attaching the mop to or detaching it from the nozzle, as well as the advantages of such a mop will be clearly understood. The mop is primarily intended, for use on a vacuum cleaner, for cleaning hard wood floors or like objects and the dust or dirt will be collected in the strands of the mop and be drawn therefrom by the usual 95 suction mechanism. The strands of the mop 100

are so positioned, and of such a length, that when suction is applied to the nozzle they will be drawn beneath the bottom edges and form a surface for contact with the floor or other object to prevent marring thereof and to form a tight fit. As previously stated the beveled side edges 9 properly position the strips 11 and the strands 12 associated therewith so that the strands will be easily drawn beneath the nozzle. The end grooves 10 form a space for the edge of the strip 11 when the mop is drawn into position around the nozzle. The fasteners 14 form an easy means for connecting the mop to or disconnecting it from the nozzle, and while I have described the socket portions of the fasteners as being carried by the mop and the headed portions secured to the nozzle it will be understood that their positions could be otherwise.

20 Where I have used the term vacuum cleaner it will be understood that the term is used in its broadest sense and includes the so-called suction sweepers and suction cleaners.

Reference is herein made to my copending application filed January 27, 1923, Serial No. 615,813.

Having fully described my invention what I claim as new and desire to secure by Letters Patent is:

30 1. In combination with a nozzle of a vacuum cleaner having downwardly and inwardly tapered side edges, a mop having a portion adapted to lie flat against the side edges of the nozzle, and means carried part by the 35 tapered side edges and part by the mop for directly connecting the mop to the nozzle.

2. In combination with a nozzle of a vacuum cleaner having recesses in its end edges and downwardly and inwardly tapered side 40 edges, a mop adapted to encircle the nozzle with a portion thereof received in the end edge recesses and a portion adapted to lie flat against the side edges, and means carried part by the tapered side edges and part by 45 the mop for detachably connecting the mop to the nozzle.

3. In combination with a vacuum cleaner including a nozzle adapted to normally contact with the surface to be cleaned and means 50 whereby a suction may be created through the nozzle, a dry mop including a plurality of strands and means carried part by the nozzle and part by the mop for direct interlocking engagement to detachably connect the mop to 55 the nozzle, the strands of the mop being of a length to be drawn beneath the under surface of the nozzle when the suction is applied to form a substantial seal between the nozzle and the surface to be cleaned.

60 In testimony whereof I hereunto affix my signature.

CLIFFORD J. GLEASON.
